UNITED STATES PATENT OFFICE.

PAUL H. DARRAH, OF BERKELEY, CALIFORNIA.

STEAM ENGINE.

Application filed October 11, 1920. Serial No. 416,031.

To all whom it may concern:

Be it known that I, PAUL H. DARRAH, a citizen of the United States, and resident of Berkeley, county of Alameda, State of California, have invented a new and useful Steam Engine, of which the following is a specification.

The present invention, while relating in general to engines, has reference more particularly to a steam engine of the rotary type. The primary object of the invention is to provide an improved type of engine which will be simple in construction and operation and also possessing other advantages which will be apparent from the following description, which will be made with reference to the accompanying drawings in which one form of the invention has been selected for the purpose of illustration.

In said drawings Figure 1 is a side elevation of the engine; Figure 2 is a top plan view; Figure 3 is an end view of the engine head; Figure 4 is a perspective view of the stator with a portion broken away to show the rotor which is also shown with a portion broken away to show the inside of two of the piston housings; Figure 5 is a perspective view of the guides for the piston rods with a portion broken away to show the anti-friction means; Figure 6 is a perspective view of one of the pistons, including the rod and the push block associated therewith; Figure 7 is a perspective view of a horizontal member which is associated with the angle plate which effects the rotary movement of the rotor, and Figure 8 is a perspective view of a frame arch.

Referring now to the drawings in detail, the engine may be assembled on a suitable base (1) of any desired size or construction, and the engine in its preferred form will comprise a stator (2) consisting of two arcuate shaped sections adapted to be joined by bolts passing through the confronting flanges as at (3). Supported by and free to rotate within the stator (2) is a rotor (4). This rotor (4) is adapted to be enclosed for a portion of its length by the stator (2) with a series of annular grooves in its circumference made to receive the rings (5) on the inner circumference of the stator so as to act as a guide for the rotor, and in this connection, oil from a suitable source, such as the cup (6), may be supplied through communicating channels to the circumference of the rotor and in the grooves for the rings (5).

This together with the anti-friction bearings shown as at (7) will be sufficient to reduce friction to a minimum.

The rotor will include a plurality of piston housings (8) which are arranged in spaced relation and longitudinal to the rotor and with axial openings (9) through which the piston rods (10) of the pistons (11) are free to reciprocate. Each one of the piston housings (8) as well as each one of the pistons (11) and their rods (10) are identical in construction.

One end of the stator (2) is provided with a flange (12) which more or less firmly grips the rotor (4) while the opposite end of the stator (2) is closed by a plate (13) which will embody in its construction a steam inlet chest (14) shown in dotted lines in Figure 3, and a steam outlet (15) also shown in dotted lines in Figure 3. The steam inlet chest (14) and the outlet or exhaust (15) are so arranged as to register with the piston housings as they are rotated around the same. Connected in communication with the intake and outlet is a steam supply piping (16) and the exhaust piping (17).

A horizontal shaft (18) extends entirely throughout the length of the engine through the rotor, and terminates at one end with a pulley or wheel (19) mounted thereon which is connected in driving relation with a pulley or wheel (20) by means of a belt or the like (21). Co-axially mounted upon the shaft of the pulley or wheel (20) is a beveled gear (22) which is adapted to mesh with the gear (23) which is carried upon the spindle (24) of the governor (25). Connected in operating relation with the governor (25) through the bell crank connection (26) is an automatic cut-off valve (27) the purpose of which is to regulate the speed of the engine by opening or closing the supply (16) when the engine exceeds its pre-determined speed or drops below the desired speed to be maintained. Mounted upon the opposite end of the shaft (18) is a wheel or the like (28) which may be used to derive power from the engine.

Each one of the piston rods is of a length to extend longitudinally of the engine almost to the end thereof, the purpose of which will presently be described.

Positioned at an angle to the axis of the rotor (4) is a plate (29) which is positioned vertically upon the base (1) and of a height at least that of the rotor. A tubular mem-

ber (30) through which the shaft (18) passes extends from the plate (29) to the supporting standard (31) for the end of the shaft (18). Each one of the piston rods 5 (10) extends through an annular slot (32) which is made in the plate (29) by producing an opening therein and presenting the flanged end of the tubular member (30) within the opening. The diameter of the 10 said flanged end is such as to leave the annular slot (32) between it and the edge of the opening in the plate. The ends of the piston rods terminate through guide bearings (33) which are arranged in spaced relation around the inner periphery of a rotatable ring (34) which is mounted in a suitable mounting (35) positioned vertically upon the base (1). The ring (34) rotates freely within its mounting (35). However, 15 to reduce friction to the minimum anti-friction bearings or the like (36) may be employed for this purpose. Suitable flanges (37) may be employed to clamp the ring (34) in place upon the mounting as best 20 shown in Figure 5. Oil for lubricating purposes may be supplied between the ring (34) and its mounting from the cup or the like (38).

To lubricate the piston rods (10) a frame 30 (35^a) is arranged adjacent the mounting (35) for the guides, which frame has a felt or the like wiper (35^b) on the side of its horizontal cross piece. Arranged above this wiper is an oil cup (38^a) which will drop oil 35 on the wiper. As the piston rods revolve they will wipe against the wiper and thus be oiled.

Carried upon each one of the piston rods 40 (10) is a slotted collar or block (39) having a beveled face (40) presented toward the face of the plate (29) and with a locking device (41) arranged to maintain the collar or block in the correct position on the rod 45 as well as to prevent longitudinal slipping of the same. In other words, each one of the blocks or collars with their beveled faces should be arranged to bear against the face 50 of the plate (29). It is of course understood that the rotor (4) is permanently fixed upon the shaft (18).

Steam being admitted from any suitable 55 source of supply through the connection (16) and with one of the piston housings registering with the intake (14), steam will be admitted to the housing and will act upon the piston to force the same outwardly; thereupon the force thus exerted will tend to slide its respective collar or block across the face of the plate (29) and as the rod is 60 guided by the annular slot (32) it will impart a rotation to the rotor which will move the next piston housing in registering relation with the intake (14) which will of course act upon the piston housed therein 65 in the same manner. Thus the desired con-

tinuous rotation of the rotor will be effected. The shaft (18) being fixed thereto will impart rotation to the wheel or other driving element for deriving power from the engine and the opposite end of the shaft will drive 70 the wheel (19) for effecting the desired governing of the engine.

I claim:

1. A steam engine, embodying a rotor, a shaft extending through the axis thereof 75 and fixedly mounted thereto, a plurality of piston housings in the rotor arranged parallel around the axis thereof, a piston in each housing, means for admitting steam to the piston housings to reciprocate the pistons 80 therein, a rod on each piston extending exteriorly of the rotor in a plane parallel to the axis of the said shaft, guides through which the piston rods extend, an abutment on each piston rod having a beveled face, and an inclined abutting surface common to all of said abutments on the piston rods 85 against which their beveled faces bear whereby the reciprocating movement of the pistons will be converted into a rotary movement of the rotor and impart a drive to said shaft.

2. A steam engine embodying a rotor, a cylindrical casing in which the rotor is confined with freedom of rotation and with 90 annular guide rings on the inside circumference of the casing received in annular grooves on the outer circumference of the rotor, a shaft on which the rotor is fixedly mounted, said shaft extending axially through the rotor on opposite sides thereof, with a driving element on one end and a 95 driven element on its opposite end, a plurality of horizontal piston housings in the rotor arranged parallel around the axis thereof 100 thereon, a piston in each housing, means for admitting steam to said housing to reciprocate the pistons therein and including governing means for controlling the port area of the steam admitting means, each of said 105 pistons having rods extending exteriorly of the rotor in a plane parallel to the axis thereof, a guide for supporting the free ends of the rods with freedom of rotation and reciprocation and means through which the 110 rods extend to said guide for converting their reciprocating movement into a rotary movement of the rotor for imparting a drive 115 to the shaft.

3. A steam engine embodying a rotor, a 120 cylindrical casing in which the rotor is confined with freedom of rotation and with annular guide rings on the inside circumference of the casing received in annular 125 grooves on the outer circumference of the rotor, a shaft on which the rotor is fixedly mounted, said shaft extending axially through the rotor on opposite sides thereof, with a driving element on one end and a 130 driven element on its opposite end, a plu-

- rality of horizontal piston housings in the rotor arranged parallel around the axis thereof, a piston in each housing, means for admitting steam to said housing to reciprocate the pistons therein and including governing means for controlling the port area of the steam admitting means, each of said pistons having rods extending exteriorly of the rotor in a plane parallel to the axis thereof, a guide for supporting the free ends of the rods with freedom of rotation and reciprocation and means through which the rods extend to said guide for converting their reciprocating movement into a rotary movement of the rotor for imparting a drive to the shaft, comprising abutments on the rods having beveled faces and an abutting surface common to all of said abutments arranged at an angle thereto and against which their beveled faces bear.
5. A steam engine embodying a rotor, a cylindrical casing in which the rotor is confined with freedom of rotation and with annular guide rings on the inside circumference of the casing received in annular grooves on the outer circumference of the rotor, a shaft on which the rotor is fixedly mounted, said shaft extending axially through the rotor on opposite sides thereof, with a driving element on one end and a 30 driven element on its opposite end, a plurality of horizontal piston housings in the rotor arranged parallel around the axis thereof, a piston in each housing, means for admitting steam to said housing to reciprocate the pistons therein and including governing means for controlling the port area of the steam admitting means, each of said pistons having rods extending exteriorly of the rotor in a plane parallel to the axis 35 thereof, a guide for supporting the free ends of the rods with freedom of rotation and reciprocation and means through which the rods extend to said guide for converting their reciprocating movement into 40 a rotary movement of the rotor for imparting a drive to the shaft, comprising abutments on the rods having beveled faces and a flat abutting surface arranged across the horizontal plane in which the rods reciprocate and at a slanting angle to the axis of the rotor and against which the beveled faces of the abutments bear substantially 45 as and for the purpose described.
10. 15. 20. 25. 30. 35. 40. 45. 50.
4. A steam engine embodying a rotor, a cylindrical casing in which the rotor is confined with freedom of rotation and with annular guide rings on the inside circumference of the casing received in annular grooves on the outer circumference of the rotor, a shaft on which the rotor is fixedly mounted, said shaft extending axially
